CLAIM

The ornamental design for a stock for a firearm, as shown and described.

DESCRIPTION

FIG. 1 is a right elevation view of the stock.

FIG. 2 is a left elevation view of the stock.

FIG. 3 is a front elevation view of the stock.

FIG. 4 is a rear elevation view of the stock.

FIG. 5 is a top plan view of the stock.

FIG. 6 is a bottom plan view of the stock.

FIG. 7 is a lower/front/right perspective view of the stock.

FIG. 8 is a lower/front/left perspective view of the stock.

FIG. 9 is an upper/front/right perspective view of the stock.

FIG. 10 is an upper/front/left perspective view of the stock.

FIG. 11 is an upper/rear/right perspective view of the stock.

FIG. 12 is an upper/rear/left perspective view of the stock.

FIG. 13 is a lower/rear/right perspective view of the stock; and,

FIG. 14 is a lower/rear/left perspective view of the stock.

The broken lines of FIGS. 3 and 7-10 are used to depict internal structure of the stock. They are included for the purpose of illustrating environment and form no part of the claimed design.
